Interview Notes

Joe Stewart Manager	Sam seemed nervous when he was interviewed. I'm not sure if this was because he is naturally nervous or if he did not know how to answer the questions that were asked.
Stu Yen Sr. Manager	Joe, I disagree...Sam was very pleasant to speak with. He was articulate and showed great initiative when he spoke about what he would do as floor manager.
Jose Mendez Manager	Sam lacked experience in stocking but was very knowledgeable about best organization practices.
Eva Luky Manager	Sam has very strong skills. He demonstrates great collaboration through prior experience.
Bob Blank Manager	I could see Sam as a part of my team in the near future.
Lauren White Manager	Sam is a solid candidate.
